Primary Examiner — Sandra S Snapp*Assistant Examiner* — Katherine Glennon(57) CLAIM

The ornamental design for a lug for a watch, as shown and described.

DESCRIPTION

FIG. 1 is a top view of a lug shown positioned on a watch depicted in broken line to indicate the watch forms no part of the claimed design;

FIG. 2 is a top view of the lug shown in FIG. 1, shown in isolation;

FIG. 3 is a bottom view thereof;

FIG. 4 is a side view thereof;

FIG. 5 is a side view thereof, showing the side opposite of that shown in FIG. 4;

FIG. 6 is a front view thereof;

FIG. 7 is a back view thereof; and,

FIG. 8 is a top perspective view thereof.

The broken lines in the drawings illustrate portions of the watch and additional lugs that form no part of the claimed design.

1 Claim, 8 Drawing Sheets(56)
